DESIGN FOR A TILTING SUPPORT FOR PHOTOGRAPHIC CAMERAS OR THE LIKE

Frederick R. Heward, Burlingame, Calif.

Application May 5, 1947, Serial No. 138,816

Term of patent 3½ years

(Cl. D61—1)

To all whom it may concern:

Be it known that I, Frederick R. Heward, a citizen of the United States, residing in the city of Burlingame, county of San Mateo, State of California, have invented a new, original, and ornamental Design for a Tilting Support for Photographic Cameras or the like, of which the following is a specification, reference being had to the accompanying drawing, forming a part thereof.

Fig. 1 is a side elevational view of a tilting support for photographic cameras or the like, showing my new design.

Fig. 2 is an end view of my design.

Fig. 3 is a top plan view of my design.

Fig. 4 is a side elevational view of my design with the tilting support elevated.

Fig. 5 is a rear view of the disclosure in Fig. 4.

I claim:

The ornamental design for a tilting support for photographic cameras or the like, as shown.
FREDERICK R. HEWARD.
